(57) **CLAIM**

I claim the ornamental design for a keyboard, as shown and
described.

DESCRIPTION

FIG. 1 is a perspective view of a first embodiment of a
keyboard;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a perspective view thereof, showing the integrated
mouse pad in a partially retracted position; and,

FIG. 9 is a perspective view thereof, showing the integrated
mouse pad in a fully retracted position.

FIG. 10 is a perspective environmental view of a second
embodiment of a keyboard illustrating an example where a
mouse is shown on the mouse pad, but disclaimed;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof;

FIG. 16 is a bottom plan view thereof;

FIG. 17 is a perspective view thereof, showing the integrated
mouse pad in a partially retracted position; and,

FIG. 18 is a perspective view thereof, showing the integrated
mouse pad in a fully retracted position.

Broken lines are for illustrating portions of the keyboard
which form no part of the claimed design.

1 Claim, 12 Drawing Sheets
